REVERSING-GEAR MECHANISM

Application filed November 13, 1922. Serial No. 600,659.

This invention relates broadly to fluid pressure operated devices, and more particularly pertains to an improved fluid pressure operated motor for transmitting motion, and especially adapted for use in reversing or otherwise changing the positions of steam engine valves, such as employed in locomotive practice.

While, for the sake of convenience, this invention is illustrated and described as a valve controlling device for steam locomotives, it will be readily understood that the invention is not limited to the specific adaptation here set forth, but finds a wide field of utility for other purposes.

The principal objects and advantages which characterize this invention reside in: the provision of improved means for transmitting motion in one of two opposite directions through prescribed limits under the application of fluid pressure; the provision of improved means for imparting and controlling motion under the application of manual and fluid pressures; the provision of improved means for imparting rectilinear motion through the application of fluid pressure; the provision of improved motion transmitting means; the provision of improved motion transmitting means characterized by the embodiment therewith of improved motion translating means; the provision of an improved fluid operated motion transmitting device; the provision of an improved fluid operated motion transmitting device characterized by the provision of improved motion translating means; the provision of improved manually controllable motion transmitting means; the provision of an improved fluid operated motion transmitting device characterized by the association therewith of improved motion translating means, and improved manual controlling means; the provision of an improved locomotive valve shifting device; the provision of an improved manually controllable locomotive valve shifting device; the provision of an improved manually controlled fluid operated locomotive

valve shifting device; the provision of an improved fluid operated steam locomotive valve shifting device; the provision of improved means for reversing the valve mechanism of a steam locomotive engine; the provision of improved means embodying manually and fluid pressure operated mechanisms for reversing the valve mechanism of a steam locomotive engine; the provision of improved means for reversing and for varying the cut-off of a steam locomotive engine, either manually or under independent power or both; the provision of improved means for controlling the cut-off and for reversing the valve mechanism of a steam locomotive engine by the application of fluid pressure; the provision of improved means for manually controlling the application of fluid pressure for varying the cut-off and for reversing the valve mechanism of a steam locomotive engine; the provision of improved means for manually adjusting the position of an element to be moved, and for applying and controlling independent pressure for aiding in the manual adjustment of the device; and the provision of an improved compact and unitary fluid operated motor adapted for installation on any standard type of steam locomotive, and manually controllable for changing the positions of the steam engine valves.

This invention is further characterized more specifically by the provision of an improved fluid operated means for changing the positions of steam engine valves for controlling the direction of motion of the engine and embodying improved manual control means; the provision of a fluid pressure operated motor for shifting the engine valves of a steam locomotive, characterized by the embodiment therein of manual control means, whereby the operator may maintain full control of the valve position at all times, and in which no great effort on the part of the operator is required for moving the valves; the provision of an improved locomotive valve reverse gear characterized by the provision of mechanism which eliminates screw and worm elements, and reduces the number of parts required; and the provision of an improved fluid operated locomotive valve reverse gear

which throughout its various positions may be positively and accurately manually controlled with safety, in which the valves are securely maintained in set position, and in which lost motion is in a large degree eliminated.

As further characterizing this invention are: improved means for developing rectilinear motion, both of the element to be moved, and the manual and other control mechanism thereof, so as to avoid pivot points and eliminate mechanical faults; the provision of a manually controlled fluid pressure operated motion imparting device wherein the manual adjustment or movement is coincident with and mechanically aided by an independent source of power; and the provision of a device possessing the foregoing features which is simple in construction, efficient in operation, and capable of universal application on steam locomotives for controlling the valve mechanism thereof.

The more specific objects and advantages which, from a structural standpoint, characterize this invention, reside in an improved cylinder and piston structure which makes for lightness, compactness and durability; the provision of an improved piston structure and motion translating element for association therewith; the provision of improved means for operating the valve which controls the fluid pressure employed in operating this device; the provision of an improved connection between the motion translating device and the element to be moved; the provision of an improved arrangement and co-ordination of manual control means, fluid pressure control valve, and motion translating means, whereby to permit of accurate and facile control of the motor and the element moved throughout the limits of travel; and the provision of an improved arrangement which operates the fluid pressure control valve for balancing the pressure on either side of the piston element when the device has been moved to a desired position for holding same against accidental displacement.

Still further objects and more specific features characterizing this invention are: the provision of improved valve operating mechanism for controlling application of fluid pressure; improved mechanism for actuating the valve by a manually controlled step-by-step motion in the same direction as that being taken by the valve, and the embodiment of these features in a unit structure.

The foregoing and such other objects and advantages as may appear or be pointed out as this description proceeds are attained in one structural embodiment, illustrated in the accompanying drawings, in which:—

Figure 1 is an elevational view of a device embodying the improvements of this invention;

Figure 2 is a similar view in top plan;

Figure 3 is a longitudinal sectional view, taken on the line 3—3 of Figure 2, looking in the direction indicated by the arrows;

Figure 4 is a transverse sectional view taken on the line 4—4 of Figure 3, looking in the direction indicated by the arrows;

Figure 5 is a view similar to Figure 4, taken on the line 5—5 of Figure 3, looking in the direction indicated by the arrows;

Figure 6 is an enlarged longitudinal sectional view taken on the line 6—6 of Figure 1, looking in the direction indicated by the arrows;

Figure 7 is an end elevational view;

Figures 8 and 9 illustrate a modified installation, of the device of Figures 1 to 7, inclusive;

Figure 10 is an elevational view, parts thereof in section, illustrating an alternate form of this invention;

Figure 11 is an end elevational view of the same;

Figures 12 and 13 are transverse sectional views taken on the planes of the lines 12—12 and 13—13, of Figure 10, looking in the directions indicated by the arrows;

Figures 14 and 15 are elevational views of detail parts of a valve employed in the device of Figures 10 to 13, inclusive;

Figure 16 is an end elevational view of another alternate form of this invention;

Figure 17 is a transverse sectional view taken on line 17—17, of Figure 16, looking in the direction indicated by the arrows;

Figure 18 discloses views of the detail parts of a valve employed in the device of Figures 14 and 15;

Figure 19 is a side elevational view illustrating one installment of the device of Figures 16 and 17 on a locomotive;

Figure 20 is an end elevational view of the same;

Figure 21 is a side elevational view of a further modified or alternate form of this invention;

Figure 22 is an end elevational view of the same;

Figure 23 is an enlarged side elevational view, parts being shown in section;

Figure 24 is a sectional view taken on the line 24—24 of Figure 23, looking in the direction indicated by the arrow;

Figure 25 is a top plan;

Figure 26 is an enlarged front elevational view of a part of the valve structure;

Figure 27 is a transverse sectional view taken on the line 27—27 of Figure 26 looking in the direction indicated by the arrows;

Figure 28 is a rear elevational view of the part shown in Figure 26; and

Figures 29 and 30 are elevational and sectional views respectively, of the valve device, Figure 30 being taken on the line 30—30 of Figure 29.

Referring more particularly to the drawings, wherein is illustrated one structural embodiment which attains the objects and features hereinbefore recited, I provide a single cylinder, generally designated 5, said cylinder being open at both ends, said open ends being closed by cylinder heads 6 and 7. The cylinder 5 is conveniently supported on any available part of the structure of the steam locomotive, when employed on such a machine, by means of the integral brackets 8-8.

The cylinder 5 is conveniently constructed with two working chambers 9 and 10, and the medial portion of said cylinder is formed into a substantially rectangular casing, as seen in cross section, at 11 in Figure 4. The opposite sides of the rectangular section 11 are provided with openings 12 and 13, which receive bearing bushings 14 and 15, said bushings having flanges 16 and 17, respectively, which are secured over the opposite side openings of the section 11, by means of machine bolts 18-18. The flanges 16 and 17, as best shown in Figure 1, are, in effect, cover plates, and the bushings 14 and 15 project into the chamber 19, within the section 11, to afford abutments 20 and 21, for a purpose which will later appear.

The top wall of the rectangular portion 11 is provided with an elongated opening 22, above which a steam or air chest or valve casing 23 is disposed, said valve casing having apertured lugs 24, integrally formed thereon, through which lugs extend machine bolts 25, said machine bolts serving to secure the valve casing on the section 11. The valve casing is provided with a threaded opening 26, to which a conduit may be connected for conducting fluid such as air or steam, under pressure, for operating the device.

Within the working chambers 9 and 10 of the cylinder 5 there are disposed pistons 27 and 28, respectively, provided with the usual packing rings 29-29, said pistons being fixedly connected together for simultaneous reciprocation by a cross-head or similar rigid beam 30. The piston 27 is connected to one end of the cross-head 30, by the provision of an axial opening 31 in the piston, and a machine bolt 32, which passes through said opening and into a threaded opening 33 in a thickened portion 34 of the cross-head. The piston 28 is similarly secured by a machine bolt 35 to a tapered web 36 which projects from the adjacent end of the cross-head 30. The reason for providing the web 36 will appear later.

The cross-head 30, in operation, is prevented from vibrating or flexing, by the provision of the cross-head guides or shoulders 37 and 38, formed integrally upon and projecting inwardly from the upper and lower portions of the rectangular section 11, the opposite longitudinal edges of the cross-head 30 having flanges 39 and 40, the outer faces

of which flanges are arcuate and seat in the complementally formed inner faces of the guides 37 and 38, respectively. Thus, displacement of the cross-head 30 from its proper position in alignment, with the longitudinal axis of the cylinder is effectively prevented.

The pistons may be generally termed as motion imparting elements, and the cross-head 30 as a motion transmitting element, and in order to derive motion from the cross-head 30, I provide a motion translating element comprising a pair of flanges 41 and 42 on the cross-head 30, afforded by the provision of the slot 43 in said cross-head. The slot 43 is disposed at an angularity of approximately eight degrees with respect to the medial longitudinal axis of the cross-head or motion transmitting element, but, of course, this angularity may be varied as found desirable. The flanges 41 and 42, being of a suitable transverse width, afford contacting or bearing surfaces 44 and 45.

Motion is translated from the cross-head 30 to a rock shaft 46, said shaft being revolvably mounted in the bushing 15 and provided with a radial arm 47, said arm abutting the inner end 21 of said bushing 15 and also abutting the adjacent side of the cross-head 30. The free end of the arm 47 is enlarged at 48, and receives a trunnion 49, carried by a rectangular block 50, which fits fairly snugly between the abutments 41 and 42. On the outer end of the rock shaft 46 there is fixedly secured a rocker arm 51, which projects downwardly as best shown in Figure 7.

The device as installed on a locomotive, assumes the position shown in Figure 1, so that the valve casing 23 is at the top, so called, and the arm 51 projects below the cylinder 5.

The rocker arm, or as hereafter termed, the reach rod connecting lever 51, has its lower end connected by a transverse pin 52, with a complemental rocker arm 53, the upper end of the arm 53 being provided with an enlargement 54 having split jaws 55-55, which receive the outer end of the rock shaft 56, and are clampingly engaged with said shaft by tightening the transverse bolt 57.

The rock shaft 56 is revolvably mounted in the bushing 14, and the inner end of said shaft 56 is annularly enlarged as at 58, said enlargement 58 having a circular axial recess 59, formed with an internal series of ring gear teeth 60. The enlargement 58 abuts the inner end 20 of the bushing 14, and the clamping jaws of the lever 53 abut the outer surface of the plate 16, so that, while permitting free rotation of the shaft 56, longitudinal displacement thereof is prevented. The enlargement 58 is provided with an arm 47^a, complemental to the arm 47, and enlarged at 48^a to receive a trunnion 49^a, provided upon the beforementioned block 50. The arms 47 and 47^a thus serve to

impart motion to both of the shafts 46 and 56.

The rock shaft 56 is provided with an axial bore 61, in which a counter shaft 62 is revolvably mounted, the inner end of said shaft 62 having a gear 63 integrally formed therewith. The gear 63 is provided with an annular enlargement 64, on one face thereof, which is adapted to abut the adjacent face of the recess 59, and a lever 65 is mounted on the outer projecting end of the shaft 63 by means of a clamping enlargement or jaw 66, said jaw 66, when properly secured, being in abutment with the outer face of the clamp 54, the enlargement 64 and clamp 66 thus preventing material longitudinal displacement of the shaft 62. The enlargement 64 furthermore spaces the gear 63 from the adjacent face of the chamber 59.

An axial trunnion 67 is fixedly secured in a valve operating lever 68, and said trunnion is provided with a head 69 which is receivable into an axial recess in the gear 63. The lever 68 is provided with radial lugs 70 on which are secured bearing pins 71, each pin carrying a freely rotatable pinion 72. The pinions 72 are in intermeshing engagement with the ring gear tooth 60 and the gear 63. There are three pinions provided, preferably disposed at 120 degrees apart. The lever 68 is retained against displacement between the abutments 41 and 42 and gear 63, (see Figure 4). The cross-head 30 is prevented against rotation or tumbling by the abutting engagement therewith of the lever 47 and valve arm 68, as best seen in Figure 4.

A valve operating lever 68 extends through the opening 22 and is provided with an enlarged head 73, said head being substantially hemispherical and lying in a recess or pocket 74, formed in the valve element 75. The valve 75 is of the conventional D-type and is disposed within the valve casing 23, and this valve controls admission of fluid under pressure to one or the other of the working chambers 9 and 10 of the cylinders. The extremities of the valve 75 are enlarged at 76 and 77 and these portions are adapted to slide upon the surface 78. Recesses 79 and 80 are provided in the under side of the portions 76 and 77, and serve to control communication between the conduits 81 and 82, and the exhaust conduits 83 and 84, respectively. The conduits 81 and 82 lead to the outer ends of the working chambers 9 and 10, and said conduits 81 and 82 are cast with the cylinder 5, but lie beyond the peripheral outer surface thereof, as will be seen in Figures 1 and 5.

When this device is installed on steam locomotives a reach rod 85, which extends from a manually or otherwise operated reverse lever in the cab, connects pivotally to an enlargement 86, formed on the lever 65, and a second reach rod 87 is pivotally connected to the pin 52, and extends and is connected to

the reverse shaft arm (not shown) which serves to elevate and depress the radius bar of a standard locomotive valve gear. The reverse lever which is located in the cab, and the parts of the valve gear have been omitted as they do not, in detail, form any part of this invention.

In the operation of this reverse gear for locomotive valve motions the degree of movement within the limits prescribed by the length of the slot 43 is controlled by the hand operated reverse lever referred to, but not shown. It will be seen, upon reference to Figures 1 and 3, that by imparting movement in the direction of the arrow A (Figure 1) to the reach rod 85, rotative motion will be imparted to the gear 63 in a clockwise direction as viewed in Figure 3, which, in turn, through the medium of the pinion 72-72 and the stationary ring gear 60, causes the valve operating lever 68 to slide the valve 75 in such direction that the conduit 81 is brought into communication with the fluid pressure inlet 26 through the valve chamber, thereby forcing the piston 27 and cross-head to the right as seen in Figure 3. Rectilinear motion of the cross-head, as referred to, depresses the arm 47, by virtue of the engagement of the abutment 41 above the block 50, and thereby imparts a partial rotation to the shaft 46, and swings the levers 51 and 53 in the direction of the arrow B, Figure 1. As the levers 51 and 53 swing in response to the action just referred to, the ring gear 60 is rotated, which automatically arrests further movement of the valve lever 68, and assuming that the operator latches the manually operated reverse lever, the piston 27, following through under pressure, returns valve 75 to the neutral or lap position shown in Figure 3, in which the valve and pistons remain, until further adjustment of the manually operated reverse lever takes place. This is true, because any attempt of the cross-head to go beyond the point at which it is set, results in a backing of the valve 75 to admit fluid under pressure to the piston 28, and thus balance the device. Ordinarily, however, the valve assumes the lap position, as seen in Figure 3, and thus serves as a lock on further movement of the piston in either direction.

Balancing of the device is best accomplished after fluid under pressure has once been admitted to both working chambers, although this is not absolutely necessary to successful efficient operation. Thus the operator is enabled to follow the usual practice of starting the locomotive with a full stroke of the engine valves, or, as commonly termed, a long cut-off, and as speed is increased the cut-off may be reduced in the usual manner, or the engine latched up. Any tendency for vibration to disturb the setting of the reverse gear of this invention is immediately compensated for by the differential gear arrangement rep-

resented by gear 63, ring gear 60, and pinions 72, so that the valve is adjusted automatically to correct any tendency for the cross-head to leave the setting desired. It will be seen that the device may be conveniently installed on a locomotive so that the operator may move the manual reverse lever, and the engine valves in either progressive steps or from full ahead to full reverse, in the same direction as that which it is desired to run the locomotive, and that the operator can, with safety and precision, control the positions of the engine valves, the same as though they were directly manually shifted. Furthermore, the absence of worms and worm gearing eliminates lost motion and reduces cost of manufacture.

The reason for the mounting of the piston 28 on the web 36 at a greater distance from the adjacent end of the slot 43, than that of the piston 27, from the other end of the slot, is that the block 50 is not in the exact medial portion of the cylinder 5, and thus without the offsetting of the piston 8, the strokes of the pistons 27 and 28 would not be properly coincidental with respect to their respective distances from the shaft 46, or medial portion of the cylinder.

Upon reference to Figures 8 and 9, it will be observed that there is provided a modified or alternate form and installation of the device illustrated in Figures 1 to 7, inclusive. The details of structure of the fluid motor, here designated in its entirety as 5^a, are substantially identical with those of the device illustrated in Figures 1 to 7, with the exception that the device 5^a is mounted, by the provision of a saddle 8^a, upon the under surface of the boiler 9^a of a locomotive, and at a point convenient to the valve gear of the locomotive, such valve gear being omitted here.

The principal object which is attained by the provision of the arrangement shown in Figures 8 and 9, is that the fluid motor is mounted adjacent to the link motion and radius rod of such link motion, thus eliminating certain connecting links and rods. The radius rod is shown in Figure 8 and designated 90, and as is common practice, is pivotally connected at one end (not shown) to a part of the valve motion known as the combination lever. However, the radius rod may be otherwise connected as far as its forward end is concerned, but the other end thereof is pivotally connected at 91 to a connecting rod 92.

The conventional supporting brackets 93 and 94 are provided, which brackets are mounted on either side of the locomotive, and are provided each with a bearing 95, in which the link (not shown) is oscillatingly mounted. As is conventional, the radius rod is pivotally connected to a block which slides in the link, so that as the outer end of the radius rod is elevated and depressed the posi-

tion of the valve stem and locomotive valve are changed for reversing the locomotive, or for regulating the cut-off. Each of the brackets is provided with an elongated opening 96, through which the radius rod 90 projects.

The fluid motor is here shown as inverted and thus the fluid pressure chest 97 is presented downwardly. The reason for this mounting is that the angularity of the slot 45^a is such that the proper motion is imparted only when the device is inverted as shown, unless the fluid motor mechanism is structurally altered. It is intended that the device of Figures 1 to 7 be employed in the installation shown in Figures 8 and 9, and therefore this change of position of the device is required. It will be observed from Figure 9 that the rocker shaft 98 extends across the locomotive and is composed of the sections 99 and 99^a, one of which may be an extension of the shaft 56, hereinbefore referred to, and the other of which may be an extension of the shaft 46.

While the two sections 99 and 99^a are independent of each other, they are simultaneously actuated because of the provision of the two arms 47 and 47^a, hereinbefore described, and best seen in Figures 5 and 6. Thus, the sections 99 and 99^a operate as a single shaft.

The shaft sections 99 and 99^a are, at their outer ends, mounted in bearings 102 and 103, provided on the top portions of the brackets 93 and 94, respectively. The valve controlling shaft 62, previously referred to, is here extended axially through the section 99, as indicated at 104, and extends beyond the outer end of said shaft section to receive a lever 105, which latter is connected to the manually operated mechanism in the engine cab.

The shaft section 99 is connected to the radius rods provided on either side of the locomotive, by the provision of arms 106—106 which are fixedly connected to the shaft sections 99 and 99^a, the free end of the arm 106, as best seen in Figure 8, being pivotally connected at 107 to the upper end of the connecting rod 92.

It will be observed from the foregoing that the installation herein provided is compact and extremely simple, especially in that it eliminates providing a long reach rod from the fluid motor to the tumbling shaft of the valve gear, in other words, that shaft which would be substituted in place of the shaft sections 99 and 99^a. Of course, this installation requires a slight modification of the conventional valve gear structure, in so far as the tumbling shaft is concerned, but as the shaft sections 99 and 99^a correspond to the conventional form of tumbling shaft, it is only necessary that this latter shaft be removed from the bearings 102 and 103 and this invention substituted therefor.

Referring now to the modified form of this

invention illustrated in Figures 10 to 15, inclusive, there is provided a cylinder 108, said cylinder having working chambers 109 and 110, the chamber 110 being closed by an integral end wall 111, and the chamber 109 being closed by removable end head 112. The portion of the cylinder 108 which defines the working chamber 110 is preferably constructed separately from the main part of the cylinder, and to this end the cylinder 108 is provided with a radial peripheral flange 113, which is in abutment with a complementary flange 114, provided on the detachable part of the cylinder, and fixedly secured thereto by the provision of a circular series of fastening screws 115.

Within the cylinder 108 there is provided a single piston 116, normally, that is when in neutral position, being disposed in the medial portion of the cylinder, said piston being longitudinally slideable in the cylinder, between the working chambers 109 and 110. A cross-head 117 is integrally formed with or otherwise fixedly connected to the piston 116, said cross-head comprising the spaced substantially flat bars 118 and 119. The longitudinal edges of said bars are provided with curved beveled surfaces 120 and 121, respectively, which are adapted to engage the internal surface 122 of the cylinder.

The bars 118 and 119 are spaced apart to receive therebetween a movable element 123 which serves to transmit motion from the cross-head to mechanism to be moved, and described later. To impart motion to the element 123, which, as shown, is a substantially cylindrical rod, the intermediate portion thereof is enlarged and flattened at 124 to form a support for trunnion shaft 125, on the free ends of which shaft are mounted rocking blocks 126 and 127, which latter lie in slots 128 and 129 in the bars 118 and 119. The slots 128 and 129 are disposed in planes angularly related to the longitudinal axis of the device, and the surfaces 130—130 thereof contact with the adjacent surfaces of said blocks 126 and 127. At or adjacent the area of contact between the blocks and the slots, the internal diameter of the cylinder 108 is enlarged, and at this point the cylinder is provided with internal wearing surfaces 131—131, which engage the bars 118 and 119. The bars forming the cross-head 117, when in either of the working chambers of the cylinder are guided by the peripheral walls thereof. As best seen in Figure 13, the rod 123 fits snugly between the bars 118 and 119 and thereby prevents rotation of the cross-head in the cylinder.

The lower end of the rod 123 is slidably mounted in a pocket 132, the upper portion of said rod passing through and being surrounded by a packing 133, said packing being sustained by socket member 134, mounted in an opening 135, in the cylinder 108, said open-

ing being bordered by an upstanding angular flange 136. A retaining plate 137 engages the flange 136 and said packing, and bolts 138—138 pass through said retaining plate for an obvious purpose.

Motion is imparted from the rod 123 to the mechanism to be moved (not shown) by the provision of a rock shaft 139, said rock shaft being revolvably mounted in bearings 40—40, provided on the standards 141—141, said standards being cast preferably integrally with the cylinder 108. The standards 141 are curved so as to bring the axis of the shaft 139 to one side of the rod 123, as best shown in Figure 10, and upon said shaft and between the bearings 140 there is fixedly secured the hub portion 142, by the provision of a key 143, a lever 144 extending from said hub 142 and having a laterally extending pin 145 which engages in a transverse slot 146, provided in an enlargement 147 on the upper end of the rod 123. The outer ends of the shaft 139 project beyond the bearings in order to receive the hub portions 148—148 of rocker arms 149—149, and the lower ends of said arms receive a trunnion 150 to which a reach rod 151 is pivotally connected.

It will be observed that as the piston reciprocates, the slots in the cross-head will impart transverse reciprocation to the rod 123 and thereby rock the shaft 139.

Fluid pressure to the cylinder for reciprocating the piston is controlled by the provision of a valve, said valve being generally designated 152 and having operative connection with manually operated means, and also with one of the arms 149, so that control of motion is entirely within the hands of the operator, and in which he may impart motion forwardly or rearwardly to the piston either in steps or in a given direction continuously within prescribed limits.

To this end the valve includes a supporting part 153 cast integrally with the cylinder 108, and provided with an air chamber 154 to which an air or other fluid supply pipe is connected. A cover plate 156 is secured to the part 153 by the provision of bolts 157, or the like, which pass through the plate 156 and into threaded openings in the part 153. The cover plate 156 is provided with an axial opening 158 forming a bearing for a valve stem 159, said stem extending into the chamber 154 and being keyed or otherwise fixedly secured to the disk valve 160.

As best shown in Figure 15, the valve 160 is cut away at 161 and is provided with a segmental groove 162, which groove is adapted to be presented toward the inner face 163 of the cover plate 156, and also adapted to be in continuous communication with an exhaust port 164 provided in said cover plate. Said cover plate is furthermore provided with spaced apart ports 165 and 166, said ports 165 and 166 and the exhaust port 164

being arranged approximately 120 degrees apart as best seen in Figure 14. The ports 165 and 166 when the cover plate is placed in position communicate with conduits 169 and 170 provided on the cylinder 108, said conduits extending to points on either side of the piston 116.

As will be observed from Figures 10, 14, and 15, the normal position of the valve 160 is such that its portions 160^a—160^a cover the ports 165 and 166, and thus exclude the pressure medium from said ports.

The valve is manually operated, that is, rotated through a certain prescribed arc by provision of crank arm 171 fixed to the outer end of the valve stem 159, and to said crank arm there is pivotally connected, at 172 a combination lever 173, the upper end of said combination lever being pivotally connected 20 at 174 to a manually operated reach rod 175, which latter extends to the engineer's cab, when the device is installed on a locomotive. The lower end of the combination lever 173 is pivotally connected at 176 to a connecting 25 rod 177, which latter is pivotally connected at 178 to the rocker arm 149.

In the operation of this device, the piston is caused to reciprocate, or to move in one or the other directions desired, by imparting 30 motion in the opposite direction to the reach rod 175. Assuming that motion is imparted to the reach rod 175 so as to displace the same toward the left hand end of Figure 10, it will be observed that the crank arm 171 will be 35 oscillated to swing the valve 160 in a clockwise direction, which motion of the valve places the port 165 in communication with the chamber 154 and admits fluid under pressure to the working chamber 109, thereby 40 causing the piston 116 to be displaced to the right in Figure 10. The angularity of the slots 128 and 129 is such that the rod 123 will be pulled downwardly, and this motion, through the shaft 139, moves the reach rod 45 151 in the direction of the arrow X, Figure 10. Thus it will be observed that the reach rod 151 and piston 116, move in the same direction on a given impulse, while the reach rod 175 may be so connected to a manually 50 operated lever (not shown) that such lever is moved in the same direction as the piston and reach rod 151. As the piston responds to the pressure, and the arm 149 is displaced to the right, the combination lever 173 will be 55 swung, by virtue of its connection through the rod 177, on the point 174 as a pivot, and thereby return the valve 160 to the neutral or lap position, thus equalizing the pressure on either side of the piston. As the lower end 60 of the combination lever is fixed at the pivot point 176 by virtue of its connection with the arm 149, it is possible for the operator to again move the reach rod 151, either in the same direction or in an opposite direction, 65 by imparting motion in the desired direction

to said reach rod 175, through the manual means provided. Of course, it will be readily understood that the reach rod 175 is connected with latching mechanism which has not been shown. Thus, it will be seen that, 70 first; the rod 177 forms a fulcrum on which the combination lever is manipulated, and secondly; after a movement of the piston, and upon a final setting of the reach rod 175, the latter forms a fulcrum for the combination lever. Therefore, with the exception of the manual setting of the valve, the degree of movement and the direction of movement taken by the piston and the distance to which same will travel on a given setting of the 75 reach rod 175 is wholly automatic. To reverse the valve gear of the locomotive the reach rod 175 is simply moved in a right hand direction as viewed in Figure 10.

Referring now to the device shown in Figures 16 to 18, inclusive, and to the installation of this device illustrated in Figures 19 and 20, it will be seen that there is provided a cylinder 180, in which is reciprocable a piston 181 having a piston rod 182, which latter is provided along one edge with rack teeth 183. The cylinder is provided with a removable head 184 at one end, and the other end of the cylinder is provided with a laterally extending portion 184, the cylinder and 90 the portion 184 being preferably one casting. The part 184 forms a chamber 184, and on said part 184 there is integrally cast or otherwise fixedly secured an upstanding portion 186 forming a chamber 187 which is in communication with the chamber 185, so as to form a complete housing for mechanism which will presently be described. The upstanding portion 186 is provided with a bearing 188 in which the locomotive valve gear 100 tumbling shaft 189 is revoluble, said bearing having a retaining plate 190 which embraces said shaft and is bolted or otherwise secured at 191 to the upstanding part 186.

As best shown in Figure 17, the cylinder 180, as seen at the right hand end of this view, is provided with an axially extending pocket 192 adapted to receive the piston rod 182 when the same is reciprocated, and the cylindrical wall 193 of the cylinder 180 serves to 110 divide the working chambers of the cylinder from the chambers 185 and 187, as best seen in Figure 16.

The rack teeth 183 are in meshing engagement with a pinion 194 revolvably mounted 120 within the cylinder 180 on a shaft 195, which shaft extends transversely of the cylinder, is mounted in a bearing 196, and is preferably integrally formed with a worm 197, the latter being revoluble in the chamber 185. Reciprocation of the piston, it will be observed, imparts rotation to the worm 197.

It is intended that the worm 197 imparts, through its rotation, motion through the shaft 189, and to this end a segmental rack 130

198 is provided on the lower end of an arm 199, said arm being in meshing engagement with the worm 197. The arm 199 is provided with a hub portion 200, which is keyed or otherwise fixedly connected at 201 to the shaft 189, and the chamber 187 is of sufficient size to permit oscillation of the arm 199 in response to rotation of the worm.

As in the devices of this invention which have been previously described, the piston 181 is moved in the desired direction by the admittance of fluid under pressure to the cylinder 180 on the proper side of the piston. To this end, I provide a valve generally designated 202 mounted on an enlargement 203 formed integrally with the portion 184. The valve here shown comprises a disk 204 fixedly mounted upon a revoluble valve stem 205, which latter lies within a bearing sleeve 206, said bearing sleeve being formed upon the secondary valve disk 207. The disk 204 is in facial contact with the disk 207, and both of said disks lie within the chamber 208, formed in the enlargement 203. The disk 207 is revolvably mounted, the sleeve 206 being arranged in an opening 209 formed in the cover plate 210, which latter closes the front of the chamber 208.

The cover plate 210 is provided with an exhaust port 211, and also is provided with communication ducts 212 and 213, which latter have ports 214 and 215 respectively, which open into the chamber 208, through certain ducts in the disks 204 and 207. The other ends of the ducts 212 and 213 connect with conduits 216 and 217, respectively, arranged for conducting fluid under pressure to the opposite ends of the cylinder. The exhaust port 211, and ports 214 and 215 are arranged about 120 degrees apart, as best seen in Figures 16 and 18.

The disk 207 is provided with a circular series of three segmental slots 218 terminating as shown in Figure 18 to afford solid portions 219—219, and in position in the valve chamber, the slots 218 register each with one of the ports 211, 214, and 215.

The disk 204 is provided with a segmental groove 220, presented toward the disk 207, and a part of the disk 204 is cut away as at 221. The lap or neutral position of the valve disk 204, and the position of the secondary valve disk 207, are such that the recess 221 is in alignment with one of the ports 219 of the secondary disk, and the groove 220 is then in registration with the lowermost of the slots 218.

Rotation of the valve 204 in either direction admits fluid under pressure through the recess 221 to one or the other of the ducts 216 or 217, via one of the slots 218 in the secondary disk 207. At the same time the other of the ducts 216 or 217 is placed in communication with atmosphere via the groove 220, slots 218, and exhaust port 211. Fluid under

pressure is supplied to the chamber 208 through a conduit 222.

Movement of the valve to its various positions is controlled manually, and the flow of fluid through the valve is further controlled by the movement of the piston 181. The primary valve 204 is manually controlled by the position of a lever 223, fixedly mounted on the outer shaft or valve stem 205. The valve disk 207, here termed the secondary valve, is operated by the provision of a lever 224 pivotally connected at its outer end to a connecting rod 225, said lever being fixedly engaged at 226 with the sleeve 206. The connecting rod 225 is bifurcated on its outer end and pivotally connected at 227 to a short arm 228, said arm having a hub portion 229 which encircles the shaft 189, and is keyed thereto as at 230.

In operation, it being understood that the lever 223 is connected to a manually operated mechanism (not shown), provided in the cab of the locomotive, a displacement of the lever 223 in a clock-wise direction brings the recess 221 into communication with the duct 215, which permits fluid under pressure to pass from the chamber 208, via one of the slots 218 in the secondary valve to the conduit 217, thence to the right hand side of the piston 181, as viewed in Figure 17. This transmits motion to the piston and this motion is, in turn, transmitted to the worm 197, thence to the arm 199, giving the necessary motion to the shaft 189. When the manually operated lever 223 is locked in the desired position, after a movement has been imparted thereto, the valve 204 is, of course, stopped. However, the shaft 189, in transmitting its motion to the connecting rod 225, rotates the disk 207, or secondary valve, in the same direction as the valve 204, and this motion continues until one of the blank spaces 219 of said secondary valve again registers with the recess 221. This automatically shuts off the supply of fluid and the piston 181 is arrested. Similarly, a motion in a counter-clockwise direction to the lever 223 will simply reverse the operation as above described, so that the movement of the shaft 189 is always within the control of the operator. It will be obvious that movement of the piston beyond the desired limit cannot be had, regardless of where the piston may be, as the disk 207 always acts as a follow-up and must move in response to the movement of the shaft 189.

There are many different applications to which the invention illustrated in Figures 16 to 18 may be adapted, but as applied to a steam locomotive valve gear the invention is installed as best shown in Figures 19 and 20. It will be observed that, in Figures 19 and 20, the tumbling shaft 189 is part of a valve gear installation similar to that partly shown in Figures 8 and 9.

Referring now to Figures 19 and 20, it will be seen that the tumbling shaft 189 extends

entirely across the locomotive beneath the boiler 9^b thereof, and the fluid motor illustrated in Figures 16 to 18, inclusive, and here generally designated 180^a, is suitably secured 5 to the under portion of the boiler 9^b by the provision of a saddle or other bracket 180^b.

The ends of the tumbling shaft 189 are mounted in bearings 189^a carried by brackets 190^a, said brackets and bearings serving to 10 support the link bearings 191^a. The conventional radius rod 90, similar to that shown in Figure 8, is provided, and pivotally connected at 91 to a connecting rod 92, the latter being pivotally connected at 231 to a lever 15 232 fixedly secured to the tumbling shaft 189 and extending laterally therefrom.

It will be observed, without further detailed description, that the rock shaft 189, when rotatably displaced by movement of the 20 piston in the cylinder 180, will impart the necessary motion to both of the levers 232 for shifting the valve motion through the medium of the radius rod 90.

Referring now to the modified form of the 25 invention illustrated in Figures 21 to 30, both inclusive, and first to Figure 21, there is provided a cylinder 235 having at one end, a removable head 236, said head being fixedly retained on the cylinder by the provision of 30 bolts or the like 236^a. At the other end of the cylinder there is provided an upstanding housing 237, said housing being, for the sake of mechanical convenience, cast integrally with the cylinder 235. The chamber or housing 237 is provided with a removable head 238 which serves, as heretofore pointed out, as a bearing for a moving part of the device. A series of bolts 239 serve to secure the head in position. It will be observed from an inspection of Figure 22 that the longitudinal 40 axis of the chamber 237 is disposed in a plane out of alignment with that of the longitudinal axis of the cylinder 235. This is done for a purpose which will presently appear.

45 The cylinder 235 is provided with integral brackets 240—240 which serve to fixedly support the whole structure at a suitable vantage point on a locomotive or other place at which the device is to be used.

50 Upon reference to Figure 23 it will be seen that a piston 241 is mounted for reciprocation in the cylinder 235, said piston being operable within the confines prescribed by the cylinder head 236 and the interior end wall 242. Thus 55 the cylinder is provided with working chambers 243 and 244, arranged on either side of the piston, and into said chambers fluid is admitted under pressure at the proper time to reciprocate the piston as desired. The wall 60 of the cylinder is provided with ducts 245 and 246 which lead to the opposite ends of the working chambers 243 and 244, respectively, flow of fluid under pressure to said ducts being controlled by the provision of a 65 valve structure generally designated 247 and

involving features of construction which will be presently pointed out.

The wall 242, previously referred to, forms an integral part of the cylinder 235, and also forms an integral part of and supports an extending chamber 248 which serves as the direct support for the valve 247 and chamber 237. As shown in Figure 23, the valve is mounted directly upon the chamber 237, but, of course, might be otherwise conveniently mounted.

The chamber 248 serves to accommodate a piston rod 249 which is carried by the piston 241 and fixedly secured axially thereto by the provision of a bolt and nut connection 250. The piston rod 249 extends through an axial opening 251 provided in the chamber 248, said chamber 248 being furthermore provided with an enlarged pocket 252, which latter is of sufficient size to receive an elongated pinion 253, said pinion and the chamber in which same is mounted being in axial alignment with the chamber 237. The piston rod 249 is preferably made flat or, in other words, substantially rectangular in 90 cross-section, and, as best seen in Figure 24, said piston rod is provided with a series of rack teeth 254 which are adapted to operatively mesh with the teeth of the pinion 253 so that as the piston reciprocates, it causes 95 the pinion to be rotated. The piston rod, which serves the purpose of a cross-head, is received in a pocket 255, which latter is provided with an annular flange 256 secured by bolts 257 to a complementary flange 258 provided on the extension 248. The pocket member 255 is provided with an internal recess 259 which is substantially rectangular in cross-section, but which recess does not in itself prevent tumbling of the piston rod. Tumbling of the piston rod is prevented by the provision of a sleeve 260, which latter is received in an enlarged portion 261 of the opening 251, said sleeve being fixedly secured 100 in position by the provision of a series of bolts 26, said bolts extending through a flange provided on the sleeve and into the adjacent part of the extension 248. The sleeve 260 is folio 5106 not printed—duplicate of folio 5107 intended to have a sliding fit with the piston rod and serves to retain suitable packing (not shown) about said rod. The sleeve is provided with a cut-away portion located adjacent the pinion 253 so that said pinion may lie in contact with the piston rod and in meshing engagement with the teeth 254.

The pocket 252 communicates with a bearing portion 263, through which the shaft portion 264 of the pinion 253 passes. The shaft 264 is fixedly connected to a worm 265, said worm being arranged axially within the chamber 237. The worm 265 is provided with an integral trunnion portion 266, which seats in a bearing recess 267, provided in an enlarged axial portion 268 of the head 238 of 130

said chamber 237. The outer end of the trunnion 266 is spaced from the adjacent surface of the bearing 267, and a thrust bearing 269 is interposed between said surface and the 5 end of said trunnion. The bearing is adjusted by bolts or set screws 270 arranged in the head 238, and lubricant is supplied to the bearing 267 from an oil or other lubricant container 271. The opposite end of the worm 265 is provided with a trunnion portion similar to that described, said trunnion portion seating in a recess 266^a provided adjacent the shaft 264, and a bearing 269^a is placed in said recess. This structure is best shown 10 in dotted lines in Figure 23.

The flanges 256 and 258 are sealed by a packing 256^a, the head 236 is sealed by a packing 237^a, and the head 238 is similarly sealed by a packing 238^a, so it will be observed that 20 fluid is prevented from escaping at these joints.

The shaft 264, which, if desired, may be made integrally with the worm 265 and have the pinion 253 keyed thereto, extends 25 through the lower part of the casing 248 and is supported and retained by a packing gland 264^a. The arrangement shown in Figure 23 permits of removal of the parts for repair or replacement without complete disassembly 30 of the apparatus.

A rocking shaft 272 is provided, said shaft being mounted in suitable spaced bearings 273-273, which latter are placed at an inclination and form an integral part of the 35 chamber 237 by the formation of said bearings on the integral webs 274-274. Within the space 275 afforded by the webs 274 and the bearings carried thereby, there is placed an angularly displaceable segmental rack 40 276, said rack being fixedly secured to the shaft 272. If desired, the shaft 272 and said segmental rack may be formed integrally. The opposite portions of the shaft 272 which lie in the bearings 273 are retained in such 45 positions by the provision of cap members 277-277. The two bearings and the space between them, as well as the space designated 274, are bridged or closed by a cover plate 278. The cover plate is readily removable 50 and also the bearings 277, so that the rack and the shaft carrying same may be readily lifted out of the device. Said cover plate is sealed by a suitable packing 277^a.

One end of the shaft 272 projects from the 55 adjacent bearing and an arm 279 is fixedly secured at 279^a to said shaft, said arm being complementary to another similar arm 280 which is fixedly secured by means of a hub 60 portion 280^a to the other projecting part of said shaft. The free ends of the arms 279 and 280 are provided with enlarged portions 281 between which is received the enlarged portion 282 of a reach rod 283, a bolt 284 extending through said portions 281 and 282

for pivotally connecting the arms 279 and 280 to said reach rod.

From the foregoing, in connection with the disclosure in the drawings, it will be observed that when the piston is moved in the cylinder 235, motion is transmitted in a given direction to the worm 265, thence to the rack 276, thereby causing the arms 279 and 280 to oscillate with the shaft 272, and impart the desired motion to the reach rod.

The valve structure hereinbefore referred to is best illustrated in Figures 25 to 30, inclusive. The valve structure includes an integral casing 285 provided upon the chamber 237, as previously explained, said valve casing having an axial abutment 286, best shown in Figure 25, said abutment being in contact with the inner face 287 of a disk valve 288, arranged for axial partial rotation in said casing 285. A closure or cap 289 is secured to the front of the casing 285, said cap being provided with a series of apertured ears 290 which register with complementary ears 291 formed on the casing 235, and through which said ears extend bolts 290^a for securing the cap 289 in position.

Fluid under pressure is supplied to the interior chamber 292 of the valve casing 285 by the provision of a conduit 293 threaded into a suitable opening 294 provided in the wall of said casing. An exhaust conduit 295 is in threaded connection with the closure plate 289, said plate being enlarged and provided with a conduit 296 which terminates on the inner face 277 of said closure plate at a 100 port 298.

The conduits 245 and 246 enter the wall of the casing 285 near the bottom thereof, as best shown in Figure 22, and said conduits 245 and 246 are in communication with ports 299 and 300 respectively, said ports forming the receiving ends of ducts 301 and 302 provided in the cover plate 289. The ducts 301 and 302 extend inwardly toward the circular face 297 of the cover plate and said ducts are provided with enlarged portions 303 and 304, said headers being substantially arcuate and arranged at approximately diametrically opposite points with respect to the circular face 297. The headers open inwardly through said face by the provision of two series of discharge ports P and P', said ports being designated 305, 306, 307, 305^a, 306^a and 307^a. The ports just referred to are arranged in their respective series equi-distantly apart 105 and serve alternately for receiving and discharging fluid under pressure. The exhaust port 298 is disposed in such a position that it lies at a point equi-distant from the adjacent ports 307 and 307^a for a purpose which 110 will presently appear.

The cover plate 289 is provided with an axial or central opening 308 in which the valve stem 309 of said valve 288 is revolvably mounted. The stem 309 is provided with a 115

flattened portion 310 upon which a crank 311 is fixedly secured, and the inner end of said valve stem is provided with a key 312 which is adapted for reception in a recess 313 provided in the front face 314 of the valve 288. The valve stem 309 is also provided with a disk portion 315 which is receivable in a complementally arranged recess 316 provided in the face 314 of said valve.

10 The disk valve, when installed in the casting 285, is arranged with the front face 314 in abutment with the rear face 297 of the cover plate, and said face 314 is interrupted by an arcuate groove 317 provided with blank

15 portions 318 and 319, the ends of said groove 317 being in communication with ports 320 and 321, said ports being arranged at points substantially diametrically opposite on the front face of the valve. The body of the valve

20 is provided with a recess 322, which recess is formed by cutting away a portion of the valve, as shown in Figure 29, this recess being of substantially the same area as that of the material between the ports 305 and 305^a.

25 Auxiliary recesses 323 and 324 are provided in the body of the valve 288 adjacent to the recess 32 and on either side thereof to form blades 325 and 326.

When the valve, in normal position, that is, lap or neutral position, is placed on the rear face of the cover plate, the blades 325 and 326 lie over the ports 305 and 305^a, and the solid portions 323^a and 324^a, between the ports 320 and 321 and the recesses 323 and 324,

35 respectively, serve to close the ports 306 and 306^a. The solid portions 318 and 319 lie over and serve to close the ports 307 and 307^a. In this position, commonly termed "lap" position, no fluid under pressure can pass the

40 valve and the apparatus is at rest.

The valve is manually operated by the provision of a lever 327 pivoted at 327^a having a latch 328 adapted to engage a segmental rack or quadrant 329, this device being mounted at a convenient point to the operator, such as in the engine cab. The lower end of the lever 327 is pivotally connected at 330 to a reach rod 331, the forward end of said reach rod being pivotally connected at 332, to the

45 upper end of a combination lever 333, the crank 311 being pivotally connected at 334 to a medial portion of said combination lever. The lower end of the combination lever is pivotally connected at 335 to a link 336, which

50 latter extends to the arm 279, and to which arm it is connected pivotally as at 337.

In operation, the engineer, when desiring to run the locomotive in a forward direction, releases the catch 328 and moves the lever 327 to the right in Figure 21. This movement will exert a pull to the left on the reach rod 331, and as the arm 279 is stationary at this time the combination lever will be moved to the left on the pivot 335 as a fulcrum.

55 This motion displaces the valve disk 288 in

a clockwise direction, and thereby admits fluid under pressure from the chamber 292 to the port 305. The fluid then flows through the port 299, conduit 245, to the left hand end or working chamber 243 of the cylinder 235, thus moving the piston 241 to the right, or toward the head 236. This movement of the piston is transmitted through the rack 254, pinion 253, worm 265, segmental rack 276, and arms 279 and 280 to the reach rod 283, thus moving said rod in the direction of the arrow X', Figure 23. This motion of the arm 279 moves the connecting rod 336 to the right in Figure 23, and as the reach rod 331 is, at this time, held against movement, the combination lever 333 will also be swung to the right and thus return the valve 288 to lap or neutral position. When the valve 288 is thus displaced in a clock-wise direction, as viewed in Figures 23 and 29, the recess 324

60 registers with one or the other of the ports 306 or 307, depending upon how far the valve is displaced, and thus if the valve is displaced to its fullest extent, the recess 322 will open both of the ports 305 and 306 and the recess 324 will register with the port 307, and thus

65 allow the full pressure of the air to be exerted upon the piston 241, thereby hastening the motion. At this time the groove 317 spans the ports 306^a and 307^a and the port 320 will

70 register with the port 305^a, thus permitting rapid discharge of the air or other fluid under pressure from the opposite end of the cylinder. The connections of the combination lever 333 are such that even though the valve is moved to its extreme limit in either direction, the arm 279 will always return the valve to lap or neutral position.

In reversing the valve gear, the lever 327 is moved to the left in Figure 21, and this movement displaces the valve 288 in a counter-clockwise direction, therefore bringing the recess 322 into registration with the ports 305^a and 306^a. This movement also brings the recess 323 into registration with the port 307^a. This permits fluid pressure to pass from the chamber 292 into the duct 246, and thereby move the piston to the left. The combination lever accomplishes the return of the valve to lap position after each movement of the lever 327. At this time the groove 317 and the port 321 serve to exhaust air from the working chamber 243.

It will be observed that the valve operates to control both of the working chambers complementally, that is, if a certain amount of air is admitted to one of the chambers, there will be exhausted from the other chamber, by the movement of the piston, a substantially equal quantity of air, and thus the piston is balanced in its movement. This balancing of the piston, coupled with the position of the worm connection as shown, effectively prevents slipping of the valve gear

or other mechanism operated by the reach rod 283.

It will be observed that in operation of the device shown in Figure 10, the reach rod 175 may be connected to a suitable lever such as that disclosed in Figure 21, and thus in all of the forms of this invention herein disclosed the operator, in adjusting the valve gear, moves the manually operated lever or other control mechanism in the same direction as the reach rod which connects the fluid motor to the valve gear or other device to be operated. Thus, in effect, the operator manually operates the valve gear, but he is substantially aided in shifting the valve gear by the interposition of a fluid pressure operated device between the operator and the valve gear. The response to movement of the manual control means by the piston is instantaneous, and the control valve mechanism as employed readily permits of an extremely accurate adjustment of the cut-off.

Having thus described my invention and illustrated its use, what I claim as new and desire to secure by Letters Patent is:—

1. In a device of the character described, in combination, a fluid pressure operated motion imparting element having a rectilinear motion translating abutment arranged at an acute angle to the axis of said motion imparting element and non-rotatably slideable in guides, a motion imparting element to be moved by and engaging said abutment, a valve for controlling application of fluid pressure to said motion imparting element, gearing having a part thereof connecting said valve to said element to be moved, and manual control means for said valve connected to said element to be moved through another part of said gearing.

2. In a device of the character described, in combination, a fluid pressure operated motion imparting element having a rectilinear motion translating abutment arranged at an acute angle to the axis of said motion imparting element and non-rotatably slideable in guides, a motion imparting element to be moved by and engaging said abutment, a valve for controlling application of fluid pressure to said motion imparting element, gearing having a part thereof connecting said valve to said element to be moved, and manual control means for said valve connected to said element to be moved through another part of said gearing, said connection of said manual control means through said gearing being such that the latter is moved in the same direction as said abutment and said motion imparting element.

3. In a device of the character described, in combination, a cylinder, a piston operable in said cylinder, a valve for controlling admission of fluid under pressure to said cylinder, manually operable means for moving said valves in one direction for admitting

fluid under pressure to said cylinder, and planetary gearing connecting said valve to be operated by said piston and to said manually operated means for moving the valve to closed position upon a movement of said piston.

4. In a device of the character described, in combination, a cylinder, a pair of pistons operable in said cylinder and connected by a cross-head disposed between said pistons, said cross-head having a rectilinear diagonal slot therein, an oscillating member engaged in said slot, a valve, manually operable means for setting the valve, and means including planetary gearing connecting said oscillating member, valve, and said manually operable means.

5. In a device of the character described, in combination, a cylinder, a pair of pistons operable in said cylinder and connected by a cross-head disposed between said pistons, said cross-head having a rectilinear diagonal slot therein, an oscillating member engaging in said slot, a valve, and means including planetary gearing connecting said oscillating member and said valve, and manually operable means connected to and for operating said valve through said planetary gearing.

6. In a device of the character described, in combination, a cylinder, a piston operable in said cylinder, a valve for controlling admission of fluid under pressure to said cylinder, manually operable means, planetary gearing within the cylinder, and means for operatively connecting said gearing to said piston, valve, and manually operable means for causing movement of the valve upon movement of the piston independently of said manually operable means.

7. In a device of the character described, in combination, a cylinder, a piston operable in said cylinder, an angularly displaceable member connected to said piston, a rotatable gear carried by said angularly displaceable member, planet gears within said first named gear, a lever operatively connected to said planet gears, and a valve for controlling admission of fluid pressure to said cylinder operatively connected to said lever.

8. In a device of the character described, in combination, a cylinder, a piston operable in said cylinder and including an inclined abutment, an angularly displaceable member connected to said piston through said inclined abutment, a rotatable gear carried by said angularly displaceable member, planet gears within said first named gear, a lever operatively connected to said planet gears, and a valve for controlling admission of fluid pressure to said cylinder operatively connected to said lever.

9. In a device of the character described, in combination, a cylinder, a piston operable in said cylinder, an angularly displaceable member connected to said piston, a rotatable

gear carried by said angularly displaceable member and disposed adjacent to said piston, a plurality of planet gears operatively connected to said first named gear, manually operated means, and means for connecting the latter to said planetary gears.

10. In a device of the character described, in combination, a cylinder and a piston operating in said cylinder, an inclined abutment operated by said piston, an oscillating motion transmitting arm connected to and operated by said abutment, a valve for controlling flow of fluid under pressure to said cylinder, planetary gearing interposed between said oscillating arm and said valve to form an operative connection therebetween and a manually operated member connected to a part of said gearing for moving said valve in one direction.

11. In a device of the character described, in combination, a cylinder and a piston operating in said cylinder, an inclined abutment operated by said piston, an oscillating motion transmitting arm connected to and operated by said abutment, a valve for controlling flow of fluid under pressure to said cylinder, a manually operable element associated with the device, a gearing having one of its gear elements connected to said oscillating arm and another thereof connected to said manually operable member and another thereof to said valve whereby to form an operative connection between said arm, valve, and manual operating means.

12. In a device of the character described, in combination, a cylinder and a piston operating in said cylinder, an inclined abutment operated by said piston, an oscillating motion transmitting arm connected to and operated by said abutment, a valve for controlling flow of fluid under pressure to said cylinder, a manually operable element associated with the device, a planetary gearing having one of its gear elements connected to said oscillating arm and another thereof connected to said manually operable member and another thereof to said valve whereby to form an operative connection between said arm, valve, and manual operating means.

13. In a device of the character described, in combination, a cylinder and a piston operating in said cylinder, an inclined abutment operated by said piston, an oscillating motion transmitting arm connected to and operated by said abutment, a sliding valve for controlling flow of fluid under pressure to said cylinder, rotatable gearing interposed between said oscillating arm and said valve and a lever connected to said valve to form an operative connection therebetween and a manually operated member connected to a part of said gearing for moving said valve in one direction.

14. In a device of the character described, in combination, a cylinder, a piston operable

in said cylinder, a motion transmitting arm operated by said piston and arranged with means for connection to an element to be moved, a valve for controlling flow of fluid under pressure to said cylinder, manually operable means for controlling said valve, and a planetary gearing having its planet gears connected to operate said valve and having its complementary gears connected to a manual control means and to said motion transmitting arm.

In testimony whereof I have hereunto signed my name.

CLARENCE CASPER BERTRAM.
